UNITED STATES PATENT OFFICE.

ROBERT H. JOHNSON, OF WASHINGTON, DISTRICT OF COLUMBIA.

VAPORIZER FOR GASOLINE ENGINES.

Application filed December 11, 1925. Serial No. 74,821.

The present invention relates to improvements in vaporizers for internal combustion engines and has for an object to provide an improved heating device in the fuel charge pipe for conveying the carbureted air to the cylinders of the gas engine.

Another object of the invention lies in providing an improved charge heating device in which a high degree of radiation of the heat will take place to the end that the entire mass of the charge passing through the pipe may be heated adequately and uniformly whereby to promote ready vaporization in the combustion chambers of the engine and complete combustion without the formation of carbon deposits.

A further object of the invention is to provide an improved heater constructed simply and inexpensively and so arranged and disposed as to permit of its installation upon the fuel charge pipe without entailing any modification or alteration therein.

With the foregoing and other objects in view, the invention will be more fully described hereinafter and will be more particularly pointed out in the claims appended hereto.

In the drawings, wherein like symbols refer to like or corresponding parts throughout the several views,

Figure 1 is a top plan view, with parts broken away, of a device constructed according to the invention.

Figure 2 is a side view of the same.

Figure 3 is a horizontal section taken on the line 3—3 in Figure 2.

Figure 4 is a vertical section taken through a portion of the charge conveying pipe with the improved device also shown in vertical section, and

Figure 5 is a plan view of the blank from which the carbon receptacle is made.

Referring more particularly to the drawings, 6 indicates the pipe which extends between the carburetor and the internal combustion engine or intake manifold and in this pipe 6, as shown in Figure 4, the improved heater is placed by installing it through a side wall of the pipe perforated for the purpose of receiving the flanged insulating sleeve 7 through which is mounted the tubular externally threaded arm 8. This arm 8 contains the porcelain or other insulating sleeve 9 through which passes one of the leads 10. The arm 8 has threaded thereon the nuts 11 and 12 for holding said

arm in place. The nut 11 is run up against the flange 7 of the insulating sleeve and this flange is forced tightly against the inner wall of the pipe 6. The outer nut 12 is screwed up tightly against the insulating washer 13 which fits against the outer wall of the pipe 6. A binding nut 14 is also threaded upon the arm 8 and cooperates with the nut 12 to hold the other lead 15 therebetween. A battery or other source of current is indicated at 16, as included in the circuit 10 and 15, together with the switch and fuse block 17 having different ampere fuses whereby to regulate the degree of the heat of the device.

The tubular arm 8 is provided with a flat extension 18 extending approximately into the center of the pipe 6 where it receives and supports the base 19 of a receptacle for holding a mass of carbon particles indicated at 20. The side wall 21 of this receptacle, which is preferably made of sheet metal, is of inverted frusto-conical shape, and is closed at its upper end by the disc cover 22 held in place by the tongues 23 extending from the upper edge of the side wall 21 and bent down over said cover. These tongues can be pried up to permit removal of the cover when desired.

The side wall 21 of the receptacle is provided with the radiating fins 24 which increase in width from the lower to the upper portion of the receptacle and are tapered or inclined at their outer edges to agree substantially with the conical taper of the side wall 21.

The extension 18 of the arm and the base portion 19 of the receptacle are both perforated to receive the insulating sleeve 25, the lower end of which engages and rests upon the insulating washer 26 fitted beneath the extension 18 and held thereto by the nuts 27 and 28 threaded upon the stem 29, which passes up through the insulating sleeve 25 and into the lower portion of the receptacle where such stem is provided with the conical head 30. The nuts 27 and 28 are adapted to receive the lead 10 therebetween. The insulating sleeve 25 extends up within the receptacle above the base 19 thereof, and, at the upper end of the insulating sleeve 25 is a relatively large wide spread flange 31. This flange is spaced below the base of the cone head 30 and it extends almost the full diameter of the receptacle at this point. The carbon particles 20 may be packed into the

base of the receptacle about the insulating sleeve 25 and beneath the flange 31.

The receptacle is constructed from a blank such as shown in Figure 5. In this blank 5 the dotted small circle 32 indicates the line bounding the outer edge of the base 19, upon which line the side wall 21 is bent up. The various fins are made by folding certain portions of the side wall upon itself. The 10 lines of flexure are three in number each fin comprising a central line 33 which is a true radius and which represents the outermost portion of the fin. The other dotted lines 34 and 35 at each side of the radial line 33 are made at an angle to the radius of the blank or receptacle and they join with the radial central line 33 at the point 36 which is the lowermost part of the fin.

In the use of the device the circuit is completed by throwing the switch 37, indicated in Figure 4, so as to direct more or less current through the device. This current passes from the battery 16 through the switch box into lead 10 which passes through 25 the sleeve insulator 9 and to the binding nuts 27 and 28, to the stem 29 and upwardly to the cone head 30 thereof, which lies embedded in the mass of carbon particles in the receptacle. The current is distributed to 30 the carbon particles over wide area by this conical head and after passing through the carbon particles, the current will gain the wall 21 of the receptacle and return through the arm 8 and its extension 18 and wire 15 35 back to the battery 16. The passage of the current through the minute carbon particles will generate heat and this heat will be rapidly picked up and given off by the metal receptacle and its fins. In fact the 40 fins possessing substantially the double walls 38 and 39 at opposite sides of the central line 33 on which the fins are folded, will provide a relative great surface against which the charge may strike and also a relatively great radiating surface for the escape 45 of the heat from the metal. Preferably a metal having a high conductivity will be selected for the receptacle.

Due to the conical arrangement of the 50 side wall 21 of the receptacle and the upwardly progressive width of the fins, the rising charge in the pipe 6 will be forcibly brought into contact with such receptacle side wall or the side walls 38 and 39 of its 55 fins. An enforced heating of the charge will result. Consequently when the charge arrives in the combustion chambers of the engine it will be completely vaporized and will be in a condition for ready and complete combustion, so that a quick starting of 60 the motor may be had and the fouling of the plugs in the combustion chambers avoided.

It is obvious that various changes and modifications may be made in the details of construction and design of the above 65 specifically described embodiment of this invention without departing from the spirit thereof, such changes and modifications being restricted only by the scope of the following claims.

What is claimed is:—

1. A vaporizer for internal combustion engines comprising a receptacle having a mass of resistance particles therein and provided with external fins, means to hold said 75 receptacle in the engine intake pipe, and a circuit including said particles and receptacle.

2. A vaporizer for gas engines comprising a inverted frusto-conical receptacle having 80 fins, a mass of resistance particles therein, means to hold said receptacle in the engine intake pipe, and a circuit including said receptacle and particles

3. A vaporizer for internal combustion 85 engines comprising an inverted substantially frusto-conical receptacle for carbon particles having fins bent from the wall thereof, said fins having double walls and inclined outer edges, means for supporting said receptacle 90 in the intake pipe of the engine, and a circuit including said particles and receptacle.

4. A vaporizer for gas engines comprising an arm insulated from the intake pipe of the engine and extending into said pipe, 95 a receptacle for carbon particles supported on said arm, a stem insulated from said receptacle and arm passing up therethrough and having a cone head thereon embedded in the particles in said receptacle, and a circuit having one side connected with said stem and the other side with said receptacle.

5. A vaporizer for gas engines comprising a hollow threaded arm fitted through the intake pipe of the engine and insulated therefrom, means on said threaded arm for securing the same to said pipe, a hollow insulating sleeve extending through said arm, said arm having a substantially flat extension, a receptacle having a perforated base fitted on said extension, a mass of carbon particles in said receptacle, a hollow insulating sleeve passing through said perforated base and said extension, a stem extending through said insulating sleeve and having a cone head at its upper end embedded in the particles in said receptacle, a wide spread insulating flange on said sleeve below said cone head, a source of current 110 connected at one side with said arm and at the other side through the first mentioned hollow insulating sleeve with said stem.

ROBERT H. JOHNSON.
